DESIGN FOR A LAST OR SIMILAR ARTICLE

William H. Joyce, Jr., Pasadena, Calif., assignor to Joyce, Inc., Pasadena, Calif., a corporation of California

Application May 24, 1941, Serial No. 101,129

Term of patent 14 years

To all whom it may concern:

Be it known that I, William H. Joyce, Jr., a citizen of the United States, residing in the city of Pasadena, in the county of Los Angeles, State of California, have invented a new, original, and ornamental Design for a Last or Similar Article, of which the following is a specification, reference being had to the accompanying drawing forming a part thereof.

Figure 1 is a rear perspective view of a last or similar article, showing my new design, the opposite side of which presents substantially the same appearance as the side shown, except that the lower central portion comprising the instep embodies a depression corresponding to the depression in the instep of a human foot.

I claim:

The ornamental design for a last or similar article, substantially as shown and described.

WILLIAM H. JOYCE, JR.
